JOHN DEAKIN, OF GLOUCESTER, NEW JERSEY, ASSIGNOR TO HIMSELF
AND D. AND C. KELLY, OF PHILADELPHIA, PENNSYLVANIA.

Letters Patent No. 73,237, dated January 14, 1868.

IMPROVEMENT IN LOOMS.

The Schedule referred to in these Letters Patent and making part of the same.

TO ALL WHOM IT MAY CONCERN:

Be it known that I, JOHN DEAKIN, of Gloucester, Camden county, New Jersey, have invented an Improvement in Looms; and I do hereby declare the following to be a full, clear, and exact description of the same.

My invention consists of certain devices, constructed and arranged as fully described hereafter, for automatically adjusting the cams which operate the heddle-levers of a loom.

In order to enable others skilled in the art to make and use my invention, I will now proceed to describe its construction and operation, reference being had to the accompanying drawing, which forms a part of this specification, and in which—

Figure 1 is a sectional elevation of a loom with my improvement, and

Figure 2 a plan view.

A A' are the side frames; α α' α'' are cross-pieces, and α^3 is the breast-beam of the loom, and in boxes secured to the side frames turn the bearings of the usual driving-shaft B. Parallel to the shaft B turns a shorter shaft, C, the teeth of a cog-wheel, b, on which, are adapted to those of a pinion, c⁴, on the shaft B, and to the shaft C are secured cams c c e. To a sleeve, D, which slides on but revolves with the shaft C, are secured cams c¹ c², and into an annular groove in the sleeve projects the forked end of a bell-crank lever, E, which is hung to the cross-piece α , and to which is connected a spring, g, secured at the opposite end to the frame of the machine, the said spring tending to maintain the lever in the position shown in red lines, fig. 2. To the cross-bar α are jointed the rear ends of heddle-levers F F' F'', which extend beneath the cam-shaft C, and are connected by cords, e, to the usual heddle-frames. On one end of the shaft B is a band-pulley, d, from which a band, f, passes to a pulley, I, on a short shaft, h, projecting through and turning in the frame A; and on the inner end of the shaft h is a pulley, m, round which, and round a pulley, n, turning on a pin near the opposite side of the frame A, passes an endless chain, G. To the chain G is secured one or more plates, i, and to the cross-piece α is hung a lever, H, one end of which is jointed to the adjacent end of the lever E, while its opposite end projects upward, opposite the pulley n, and almost in contact with the edge of that portion of the chain G on the said pulley. On each of the levers F F' is a projection, o, against which bears one of the cams c, and on the lever F' is a similar projection, against which bears one of the cams c¹ c². Inasmuch as the mechanism for throwing the shuttle and operating the threads is similar in this loom to that in looms of the usual construction, and as such mechanism is well known to persons skilled in this class of machinery, further description of the same will be unnecessary.

As the shaft B revolves, a rotary motion will be imparted to the pulley m, and the chain G will be carried in the direction of its arrow. The cams c c¹ will revolve in contact with the levers beneath them, and each lever, with the heddle-frame to which it is connected, will be alternately elevated and depressed. So long as the above-described operations continue, the pattern in the fabric produced will not be changed. When, however, one of the plates i on the chain G is brought against the lever H, the latter, with the lever E, will be turned to the position shown in fig. 2, and the sleeve D will be moved laterally, until the cam c¹ passes from contact with the lever F', and the cam c² is above and in contact with the said lever, the operation of which will thus be so varied as to alter the pattern in the fabric. When the plate i passes from contact with the lever H, the latter, the lever E, and the sleeve D, will be moved to their original positions by the action of the spring g, when the lever F' will again be under the control of the cam c¹. By the above-described arrangement of the pattern-chain G and levers E and H, in respect to the adjustable cams, the usual complex and expensive devices for adjusting the cams are dispensed with, and the loom is more certain in its action, and less liable to get out of order than those constructed in the usual manner. A greater number of cams may be secured to the sleeve D, or an adjustable shaft, having a double set of cams, may be used. The lever H may be dispensed with, by extending the arm of the lever E so as to occupy a position where it will be acted upon by the plates i.

I claim as my invention, and desire to secure by Letters Patent—

The combination and arrangement of the heddle-levers, pattern-chain, and adjustable cams, with levers E H, or their equivalents, the whole being constructed and operating substantially as specified.

In testimony whereof, I have signed my name to this specification in the presence of two subscribing witnesses.

JOHN DEAKIN.
